(57) **CLAIM**

The ornamental design for a set of LED navigation light for watercraft, as shown and described.

DESCRIPTION

FIG. 1 is a top plan view of a set of LED navigation light for watercraft of the invention illustrated positioned within a watercraft hard top;

FIG. 2 is a front and top perspective view of a bow thereof;

FIG. 3 is a bottom view thereof;

FIG. 4 is a front view thereof;

FIG. 5 is a rear view thereof;

FIG. 6 is a right side view thereof;

FIG. 7 is a left side view thereof;

FIG. 8 is a top and front perspective view of a stern thereof;

FIG. 9 is a top view of the stern thereof;

FIG. 10 is a front view of the stern thereof;

FIG. 11 is a rear view of the stern thereof;

FIG. 12 is a right view of the stern thereof; and,

FIG. 13 is a left view of the stern thereof.

The broken line showing portion of a set of LED navigation light for watercraft is included for illustrating environmental structure and forms no part of the claimed design.
